US00D861428S

(12) **United States Design Patent** (10) **Patent No.:** **US D861,428 S**
(45) **Date of Patent:** **** Oct. 1, 2019**

(54) **FOOD PROCESSOR**

- (71) Applicant: **SharkNinja Operating LLC**,
Needham, MA (US)
- (72) Inventor: **Cory Smith**, Auburndale, MA (US)
- (73) Assignee: **SHARKNINJA OPERATING LLC**,
Needham, MA (US)
- (**) Term: **15 Years**
- (21) Appl. No.: **29/673,938**
- (22) Filed: **Dec. 18, 2018**

Related U.S. Application Data

- (63) Continuation of application No. 29/611,681, filed on
Jul. 24, 2017, now Pat. No. Des. 840,745.
- (51) **LOC (12) Cl.** 31-00
- (52) **U.S. Cl.**
USPC **D7/413; D7/376; D7/378; D7/412**

OTHER PUBLICATIONS

Application for Registration of an Industrial Design Examiner's Report; Canadian Application No. 172856; Date of Mailing: May 31, 2017; 3 Pages.

(Continued)

Primary Examiner — Ricky Pham

(74) *Attorney, Agent, or Firm* — Cantor Colburn LLP

(57) **CLAIM**

The ornamental design for a food processor, as shown and described.

DESCRIPTION

FIG. 1 is a perspective view of a food processor container with lid, showing my new design in a first embodiment;

FIG. 2 is a front view of the embodiment shown in FIG. 1;

FIG. 3 is a rear view of the embodiment shown in FIG. 1;

FIG. 4 is a side view of the embodiment shown in FIG. 1;

FIG. 5 is another side view of the embodiment shown in FIG. 1;

FIG. 6 is a top view of the embodiment shown in FIG. 1;

FIG. 7 is a bottom view of the embodiment shown in FIG. 1;

FIG. 8 is a perspective view of a food processor container with lid, showing my new design in another embodiment;

FIG. 9 is a front view of the embodiment shown in FIG. 8;

FIG. 10 is a rear view of the embodiment shown in FIG. 8;

FIG. 11 is a side view of the embodiment shown in FIG. 8;

FIG. 12 is another side view of the embodiment shown in FIG. 8;

FIG. 13 is a top view of the embodiment shown in FIG. 8;

and,

FIG. 14 is a bottom view of the embodiment shown in FIG. 8.

The broken lines in the figures are for environmental purposes only and form no part of the claimed design.

The oblique line shading represents transparent, translucent or reflective surfaces.

1 Claim, 12 Drawing Sheets
